EARTH DRILLING SYSTEM

Frederic W. Hild, Los Angeles, Calif.

Application March 27, 1925, Serial No. 18,789

12 Claims. (Cl. 255—19)

My invention relates to systems of motor control and it has particular relation to such systems as are employed in connection with earth-drilling and the like.

5 In my copending application, Serial No. 454,451, filed March 22, 1921, (Patent No. 1,808,222, issued June 2, 1931,) for a Power transmission system, I have shown an electrical system that is particularly adapted for earth drilling, wherein a 10 pair of motors are connected to opposite sides of a differential gear device, the intermediate or ring-gear member of which is connected to a cable-winding drum for controlling the drilling member in the usual way. As fully explained in 15 the above identified application, one of the motors directly drives the rotary-table for operating the drill, while the other motor performs a regulating function to control the rate at which the drill-bit is fed.

20 In rotary-drilling, the limiting factor in rapid drilling is the strength of the drill pipe. The torsional load on the pipe depends upon the length and the weight of the suspended pipe.

An object of my invention is to provide load-responsive means for automatically relieving the pressure on the drill-bit in the event of a prolonged overload.

25 Drillers have become accustomed to applying considerable weight, particularly when using a fish-tail bit, to the extent of 7 to perhaps 15 tons. It is obvious that the torque required under such heavy pressure must be very great, if not excessive. Furthermore, the pipe will bend under its own weight and, during rotation, produce fiber stresses in the pipe and coupling members sufficient to cause crystallization and breakage of the metal. I have found that under average conditions, a pressure of one ton is sufficient for satisfactory drilling. Many drillers will observe proper 30 load limitations when so directed, but it is another object of my invention to provide automatic means, independent of manual control, for maintaining the desired load limit.

35 My invention will be best understood by reference to the accompanying drawing in which the single figure is a diagrammatic representation of circuits and apparatus embodying my invention.

40 I employ a differential-gear mechanism 1 of a character similar to that described in the above-mentioned copending application. The planetary gear members 2 are directly connected to drive the shaft 3 at a speed dependent upon the respective speeds of the drilling motor 4 and the hoisting or feed motor 5. These motors are preferably of the alternating-current wound-rotor

induction type having their primary circuits controlled respectively by switches 6 and 7. Speed-regulating means comprising resistors 8 are provided for the drilling motor 4 and similarly resistors 9 are adapted to control the speed of the feed motor 5. In addition to manual control of resistors 9, I employ a contactor 11, which when energized, excludes resistor sections 12, 13 and 14 from circuit.

45 The operating coil 15 of switch 11 is connected to a source of alternating-current energy comprising conductors 16, 17 and 18 which also supplies the motors 4 and 5. The switch 11 is controlled by means of a time-element relay 21, which is energized in accordance with the value 50 of the current traversing the current-coil 22 of a watt-hour meter 23. Other suitable means may be provided for current control but the customary watt-hour meter affords a convenient source to which relay 21 may be connected. The usual 55 rotary drill-table 24 is operatively connected through chain-gearing 25 and the gear mechanism 1 to the drilling motor 4. The hoist drum 26, for feeding the drilling tool, is conveniently driven by chain-gearing 27 from the differential 60 shaft 3.

65 During normal drilling operations, the relative speeds of motors 4 and 5 are adjusted manually by means of resistors 8 and 9 so that, as the drilling process proceeds, the tool is gradually fed or advanced in accordance with the comparatively slow rotation of the differential shaft 3. Normally, a considerable portion of resistor sections 9 are in the secondary circuit of motor 5, in accordance with the required speed reduction.

70 In the event of a predetermined overload on the drilling motor 4, current-relay 21 will be sufficiently energized to close its circuit and energize contactor 11, which in turn closes to exclude resistor sections 12, 13 and 14, therefore increasing 75 the speed of the feed motor 5. This increase in speed may, of course, be of any predetermined value so as to retard or stop the rotation of the differential shaft 3, and relieve the strain on the drill-bit and the drilling pipe, until the obstruction has been overcome. When normal drilling 80 conditions obtain, and the load current is sufficiently reduced, relay 21 opens to permit the reinsertion of resistors 12, 13 and 14 and to effect a reduction in the speed of the feed motor 5 and 85 a continuance of the normal drilling functions.

90 Modifications of my invention may occur to one skilled in the art and I desire, therefore, that my invention shall be limited only in accordance 95 with the scope of the appended claims.

I claim as my invention:

1. In a drilling system, in combination, a drill, draw-works for supporting the drill, a rotary table for operating the drill, a motor for operating the rotary table and draw-works, a differential drive interposed between the motor and the operated rotary table and draw-works, an auxiliary motor for operating the rotary table, said auxiliary motor being disposed to cooperate in operating the differential drive and time-limit means controlled by the load on the auxiliary motor for dividing the rotary-table load between the motors to meet operating conditions.
2. In a drilling system, in combination, a drill, a draw-works for supporting the drill, a rotary table for actuating the drill to perform drilling operations, a motor for actuating the rotary table and draw-works, means for dividing the torque delivered by the motor between the rotary table and draw-works, an auxiliary motor disposed to cooperate in operating the rotary table and time-limit means controlled by the load on the auxiliary motor for dividing the rotary-table load between the motors as the weight of the drill on the draw-works varies.
3. In an earth-boring system, in combination, a drill, means for suspending the drill in a position to perform working operations, means for rotating the suspended drill to perform the drilling operations, a motor for actuating the drilling suspending means and the drill-rotating means, an auxiliary motor disposed to cooperate in actuating the drill-rotating means and time-limit means controlled by the load of the auxiliary motor for dividing the drilling load between the motors in a predetermined ratio.
4. The combination with a rotary drilling machine comprising a drilling tool and a driving motor therefor, of a second motor for controlling the tool, a differential mechanism controlled by said motors, means responsive to movements of a planetary member of said mechanism for effecting feeding movements of said tool, manually operable means for adjusting the speed of said second motor to control the tool-feeding and current responsive means dependent upon the load of the driving motor and time-limit means controlled by the current-limit means for further controlling the speed of said second motor independently of said manually operable means.
5. A transmission mechanism comprising a driven member, a feed mechanism for the driven member, two motors for driving the driven member, a source of electrical energy for the motors, a differential mechanism for transmitting power from the two motors to the driven member and for communicating the torque of one motor to the feed mechanism and time-limit means for regulating the proportion of the torque supplied by each of the motors by controlling the supply of current to them and means responsive to the load of one motor to control the time-limit means.
6. In an earth-boring system, in combination, a boring device, control mechanism for operating and controlling the operation of said boring device, a plurality of motors for operating said control mechanism, a source of electrical energy for the motors, a differential gear mechanism, said motors being coupled to the control mechanism through the differential gear mechanism, and means for automatically controlling the supply of current to one of the motors to vary their relative torques in accordance with the resistance encountered to the actuation of the boring device.
7. In an earth-boring system, a drill disposed to operate under a feeding pressure resulting from the action of gravity upon it, a hoisting mechanism connected to the drill, a motor for operating the drill, means for transmitting power from the motor to the drill and for exerting the torque of the motor upon the hoisting mechanism to exert a force upon the drill in opposition to the force exerted by gravity to obtain a uniform feeding pressure, a second motor operatively connected to the drill for assisting the first motor, and time-limit means controlled by the load on the motor operating the drill for varying the proportion of the total power exerted by each motor to change the uniform feeding pressure.
8. In an earth-boring system, in combination, a drilling element comprising a drill bit and a relatively heavy drill stem for rotating the drill bit, said drill stem being disposed in such manner that its weight tends to force the drill bit downwardly, a motor for driving the drilling element, a feeding mechanism for exerting a force on the drilling element in the upward direction, a differential mechanism for transmitting power from the motor to the drilling element to rotate it and for exerting torque to operate the feeding mechanism whereby the force exerted by the feeding mechanism is in direct proportion to the torque exerted by the motor, a second motor operatively connected to the drilling element for assisting the first motor, time-limit means operable after the lapse of a definite time for regulating the proportion of the total torque exerted by each motor to adjust the feeding pressure and means responsive to the load of said second motor for controlling said time-limit means.
9. A boring mechanism, comprising a driven element, a feed mechanism for the driven element, two motors for driving the driven element, a source of electrical energy for the motors, a differential mechanism interposed between one of the motors and the driven element through which substantially all of the power of said motor is transmitted to the driven element and the reaction torque thereof is utilized to operate the feed mechanism and means for automatically varying the ratio of current input to the two motors to thereby regulate the torque exerted by one of the motors upon the feed mechanism to change the boring pressure.
10. In an earth-boring system, in combination, a driven element, an electrical motor for driving said element, a source of electrical energy for said motor, a feed mechanism for the driven element, a differential mechanism interposed between the motor and the driven element and operatively connected to the feed mechanism whereby the power of the motor is transmitted to the driven element and the reaction torque of the differential mechanism is utilized to operate the feed mechanism, a second electrical motor connected between the differential mechanism and the driven element for assisting the first motor and means for automatically varying the ratio of the current supplied to the two motors to regulate the torque of the first motor and consequently the torque exerted upon the feed mechanism for the purpose of regulating the feeding pressure in such manner that the total torque applied to the driven element will be maintained substantially constant.
11. In an earth-boring system, the combination with a drilling mechanism, of a differential mechanism, comprising three elements for transmitting power to the drilling mechanism, two electrical motors for driving the drilling mechanism.

- one of said motors being connected to one element of the differential mechanism and the other motor being connected to a second element of the differential mechanism, a feed mechanism 5 operatively connected to a third element of the differential mechanism in such manner that it is normally responsive to the torque of one of the driving motors, said third element of the differential mechanism being disposed to transmit power from said first element to the second element, means for transmitting the sum of the power of the two motors from the second element of the differential mechanism to the drilling mechanism and means for automatically controlling 10 the supply of current to the motors to regulate the proportion of the total power supplied by each of the motors and, consequently, to regulate the ratio of the torque applied to the feed mechanism to the torque applied to the 15 drilling mechanism.
12. In a drilling system, in combination, a drill, a motor for operating the drill, means for exerting a force tending to feed the drill towards the material being drilled, a retracting mechanism for exerting a force in opposition to the feeding force, a differential mechanism for transmitting power from the motor to the drill and for exerting torque to operate the retracting mechanism whereby the force exerted by the retracting mechanism is in direct proportion to the torque exerted by the motor and, consequently, the drilling pressure is inversely proportional to the drilling torque, and a second motor operatively connected to the drill and means whereby the inverse relation of the drilling pressure to the drilling torque may be automatically regulated by adjusting the ratio of the torques exerted by the two motors. 20
